METHOD AND MEANS FOR CONTROLLING
COMBUSTION ENGINES

Harlow B. Grow, Freeport, N. Y.

Application February 24, 1941, Serial No. 380,094

20 Claims. (Cl. 123—106)

The present invention broadly relates to internal combustion engines and especially to engines of the fuel injection type, such as Diesel motors, and to the method and means whereby their operation, speed or power may be controlled.

In present-day practice injection type internal combustion engines, especially in Diesel engines, the speed and power output control of such engines is being accomplished by changes in volumes of fuel charges introduced into the engines. In Diesel engines, wherein the ignition or combustion of the fuel charge is predicated upon the rise in temperature of compressed air within the engine cylinder, fuel of a relatively high flash point is used, such as fuel oil or so-called Diesel oil, the flash point of which should be in the neighborhood of 150 degrees Fahrenheit or more, as compared with the far lower flash point of gasoline used in other types of combustion engines. Due to the high flash point of the fuel, it is essential, in order to facilitate ignition of the fuel without undue lag, that the fuel be atomized into a very fine spray or mist. Obviously in order to promote proper atomization and uniformity of a given fuel charge, the volume and density of the fuel injected and the pressure at which it is introduced, must not appreciably change.

In controlling the operating speed and power of present-day engines, and especially of high-speed Diesel engines employed in aircraft, difficulty is encountered in running the engine at low speed and in idling it down, in the way it is possible with gasoline engines. Attempts of lowering the number of revolutions of high-speed Diesel engines, say to between one fourth to one eighth of the normal speed, usually cause an uneven running of the engine and often result in a complete stoppage, for the reason that the quantity of injected fuel becomes so small that usually employed injection pumps can no longer handle the fuel or bring it under a sufficient pressure for proper atomization. The fuel injection systems used at the present time in Diesel engines may be divided into three representative classes:

1. A system using self-metering, high pressure pumps, known as jerk pumps, individually connected with their respective engine cylinders, which pumps meter and compress the fuel charges, and in conjunction with which fuel injectors are employed for atomizing and admitting the fuel charge into the engine cylinder.

2. A system employing high-pressure, plunger-type pumps, serving a plurality of engine cylin-

ders, and adapted to maintain fuel in a container at constant pressure, from which container the fuel is conveyed to the individual engine cylinders, each equipped with a mechanically operated injector.

3. An individual compressor system in which small compressors or injector cylinders and pistons are used to compress a fuel-rich charge of fuel and air prior to injecting such charge through an automatic valve into the engine cylinder.

Pumps or compressors employed in the first and third systems mentioned, are rather complicated in their arrangement and often fail to properly function, and sometimes break down completely.

The pumps or compressors of all three systems enumerated may be classed as "constant-stroke" devices. In addition to these, many engine designers equip motors with "variable-stroke" pumps, wherein the stroke distance of the piston may be altered during operation. The mechanism for changing the piston stroke considerably adds, to the already complex construction, another cause for a possible breakdown. Moreover, present-day systems employing either variable-stroke pumps, or constant-stroke pumps, involve a further serious disadvantage, in that they do not provide for satisfactory atomization of the fuel charges, when the volume of the latter varies.

As has been stated before, it is necessary, in order to assure instantaneous combustion of high flash point fuel, that the latter be thoroughly broken up or atomized into a very fine spray, otherwise an undesirable lag in ignition, or even a total ignition failure will be experienced.

Correct atomization depends upon two major factors, i. e. pressure and volume, and in a lesser measure upon the density of the charge. Injectors employed in high-speed Diesel engines are therefore designed to produce the desired fuel spray for a given volume introduced at a given pressure. When either the volume or the pressure or both are altered, the character of the spray will materially change, unless the adjustment of the injector is changed accordingly.

Obviously such adjustment of injectors in an operating engine could be made only by still further complicating the engine control mechanism, and while attempts in that direction have been made, so far no practical solution has been found. Thus in present-day practice the setting of injectors is necessarily fixed for best atomization values within a relatively narrow range of pressures and volumes at which fuel is introduced.

From the above explanation it will become quite clear that when the engine is to be throttled down, present-day pumps or compressors of the metering type, or pumps with variable stroke, will deliver to the injector a fuel charge of lesser volume. By the same token, when the throttle is opened, a correspondingly greater volume of fuel will be injected. These charges in fuel volume cause a considerable fluctuation of injection pressure.

In order to maintain uniform and positive operation of a high-speed engine at any speed, correct and positive ignition of each successive fuel charge introduced into the engine must be assured.

The herebefore enumerated systems and devices do not meet this requirement, since they do not effect at all engine speed, the essential uniformity in volume and pressure, and consequently do not provide uniformity of the successive fuel charges injected into the engine, when its speed or power varies. This lack of fuel charge uniformity causes uneven engine operation, poor acceleration and possible engine stoppage.

From the foregoing explanatory matter the numerous disadvantages of present-day control devices for compression-ignition engines, and the lack of satisfactory speed and power control of such engines becomes readily apparent.

The present invention has for its principal purpose the elimination of these disadvantages and to provide positive and dependable speed and power control for high-speed injection-type or Diesel engines, whereby it is made possible to assure accurate injection and ignition timing, to regulate the rate and effective power output of fuel charge injections, and to maintain such injections at a constant, predetermined volume and at an approximately uniform pressure, thereby facilitating great flexibility in varying the power output of an engine.

One of the objects of the present invention is the method of controlling the operation of internal combustion engines by varying the combustibility or power effect of the successive fuel charges introduced into the engine, without changing the volume of such fuel charges, nor materially varying the pressure at which they are introduced, and wherein these fuel charges comprise, at the moment of their injection into the engine, liquid matter only, containing neither gases nor air, thus virtually constituting what is known as "solid liquid fuel injections," which I shall hereinafter term "solid injections."

Another object of the present invention is the method of controlling the operation of high-speed internal combustion engines by changing, at will, from normal engine fuel to a mixture of such normal engine fuel with another liquid agent, or vice versa, and by altering the composition of such mixture without changing the volume of, or the pressure at which fuel charges of either normal engine fuel or of such mixture are introduced into the engine.

Another object of the present invention is the method of regulating or varying the speed and power of high-speed injection-type internal combustion engines, consisting of mixing with the normal engine fuel, having certain combustion characteristics, an agent having different characteristics from that of the normal engine fuel, and injecting fuel charges of either normal engine fuel, or of the mixture, at constant volume and without materially changing the pressure at

which such fuel charges are introduced, thereby altering the effective power output of the engine.

Still another object of this invention is the method of reducing the speed or power of high-speed Diesel type engines, which method consists of mixing normal engine fuel of a certain heat value with an agent having a lesser heat value than that of the normal fuel, immediately prior to the introduction of a fuel charge into the engine, without changing the normal volume of such fuel charge, nor materially altering the pressure at which such fuel charge is introduced, thereby lowering the effective power of such fuel charge.

15 Another object of this invention is the method of controlling the operation of Diesel engines by changing the combustibility of the successive fuel charges introduced into the engine, without altering the normal volume of the fuel charges, nor materially altering the pressure at which the fuel charges are introduced, and wherein the fuel charge is composed of normal engine fuel mixed with an inert agent, which mixture is strongly emulsified prior to the introduction of the fuel charge into the engine, whereby the normal engine fuel becomes finely distributed and diffused within such agent, thereby changing the physical structure of the fuel charge.

Still another object of this invention is to provide suitable means, appropriately connected with injection type high-speed engines, which facilitate the introduction into the engine of a fuel charge containing either normal engine fuel, or a fuel charge consisting of a mixture of normal engine fuel and another agent, designed to alter the effective power output of the normal engine fuel, and which means are provided with suitable instrumentalities for operating them so that the proportion of normal fuel to such agent may be readily changed, as desired, while the engine operates.

Another object of this invention is to provide suitable mechanical means for putting into effect the aforesaid methods, which means consist of various instrumentalities for controlling the flow of fuel and of another liquid agent, for mixing liquids, for emulsifying or diffusing them, to assure relative uniformity of the mixture prior to its injection into engines in the form of fuel charges, and means for injecting uniform fuel charges of constant volume, and introduced at substantially a constant injection pressure, at any engine speed.

The foregoing and a number of other objects and important advantages of the present invention will become more fully apparent from the ensuing description, in connection with the accompanying drawings, which latter are held in a more or less diagrammatical form and are intended to serve for explanatory purposes only, and are not designed to limit the present invention to the specific structures illustrated.

As has been explained previously, high-speed injection-type internal combustion engines or Diesel engines, primarily employed for aircraft, possess as their standard equipment various types of injector pumps or compressors, by means of which fuel is introduced into the engine cylinders. All these devices are more or less calculated for certain volumes of fuel charges injected at a certain injection pressure for producing the normal speed or power of the engine. When it is attempted to operate an engine at a lower speed or with less power, by reducing either the volume of fuel charges or the pressure at

which they are introduced, the pumps or compressors can no longer efficiently handle the fuel, and the required atomization by the injectors of the fuel charge, lacking in volume, cannot take place. This results in what is known as "missing" of the engine, and often causes engine stoppage. Metering pumps or variable stroke pumps designed for regulating speed or power of such engines are unsatisfactory. They are not only costly, but their operating mechanism is so complicated that they are often subject to erratic operation, precipitating a total breakdown.

The present invention is designed to control the operation of engines not by changing the volume and density of fuel charges, but by changing their combustibility or power effect when injected into an engine cylinder, thus assuring the required volume and pressure for proper atomization of such fuel charge. This change in combustibility or power effect of fuel charges is accomplished by what may be termed "dilution or diffusion of the normal engine fuel."

In the ensuing description and in the appended claims certain expressions will be found intended to simplify their wording. For this reason it may be well to elucidate these expressions.

Thus, for instance, under "normal or active engine fuel" is to be understood a fuel which is normally used in the type of engines indicated, such as Diesel fuel oil for Diesel engines.

Under "fuel charge" will be understood a certain volume of introduced fuel of either normal engine fuel, or a mixture containing such normal fuel and an agent having combustion characteristics different from normal fuel.

The words "normal fuel charges" designate fuel charges containing only active or normal engine fuel. The words "normal engine speed" define the speed of an engine attained while developing its normal power for which it is designed. For example, an engine is designed to normally produce 1200 H. P. at a normal speed of 2500 R. P. M.

The term "diluting agent" designates a liquid with which normal engine fuel is either mixable, or with which it may be emulsified; such agent or carrier may either be an inert liquid which is not combustible, or a liquid having combustion characteristics or heat values different from that of the normal engine fuel, and which heat values may be either higher or lower than that of the normal fuel.

The word "dilution" does not only mean the usual physical dilution, such as is possible with water and alcohol, but rather a mixture, or an emulsion, or a composition of liquids, wherein one of the liquids is normal engine fuel, which is finely and uniformly distributed within a liquid different from the normal engine fuel. The words "diffusion" or "diffusing" also indicate the uniform distribution of normal engine fuel in the body of another liquid.

The terms "controlling or regulating the operation of an engine" relates to changes in either the speed, R. P. M., or power, H. P., of an engine.

Having thus clarified the meaning of the different expressions to be employed in this application, reference is now made to the accompanying drawings, wherein

Fig. 1 is a more or less diagrammatical illustration of one possible arrangement of mixing valves, injector pump and supply means employed for accomplishing the method indicated;

Fig. 2 illustrates a vertical cross section through a modified valve structure;

Fig. 3 is a cross sectional view taken on line 3—3 of Fig. 2;

Figs. 4 and 5 illustrate other forms of valve structures;

Fig. 6 shows a still different embodiment of a valve structure, including an emulsifier;

Fig. 7 is a vertical cross section through a partly diagrammatical illustration of an injector pump and injector arrangement;

Fig. 8 is a section taken on line 8—8 of Fig. 7; Fig. 9 is a diagram showing a chart of an injection.

Fig. 10 is a diagram showing the timing of an injection; and

Fig. 11 represents a partial side elevation in fragmentary section of an engine showing diagrammatically the employment of the present invention.

The underlying principle of the present invention resides in the feature of regulating the speed or power of an engine by changing the physical character, the heat value or the effective power of injected fuel charges, without changing their volume or appreciably altering the pressure at which they are introduced.

Referring to Fig. 1, there is indicated a container 10, representing supply means for normal engine fuel, and another container 11 representing supply means for a diluting or diffusing agent, such as water, carbon tetrachloride, or any other inflammable, or non-inflammable, or inert liquid. Both containers are connected by suitable conduits to a valve structure 12, constituting a mixing chamber for both the fuel and the agent. This structure is provided with an opening 13, connected with tank 10, and opening 14, connected with tank 11, which openings issue into ports 15 and 16, respectively, and which ports are respectively controlled by threaded rotary valve stems 17 and 18. Ports 15 and 16 connect with a mixing space 19, from which leads a single conduit 20 to fuel injector pump 21, wherein operates a piston 22. Pump 21 is connected with an engine cylinder indicated at 23. It is to be noted that, while pipe or conduit 20 is shown relatively long, it is essential that the connection between valve structure 12 and pump 21 be as short as practicable. The reason for this statement will become presently evident.

Valve stems 17 and 18 are provided with gears 24 and 25, respectively, which mesh with one another and are preferably of the same diameter and contain the identical number of teeth. In engagement with one of the gears is an operating gear 26, which may be driven by any suitable mechanism. Thus when gear 26 is moved, its motion is transmitted to gears 24 and 25, whereby the threaded stems 17 and 18 will be moved oppositely to one another in longitudinal direction, so that one of the stems will either reduce the passage through, or completely close one port, while the other stem will simultaneously increase the passage through, or completely open the other port. Depending upon the direction of rotation of gear 26, the sequence of the reciprocal closing or opening of the two ports will take place.

From the explanation of the crude arrangement shown in Fig. 1 it will be quite evident nevertheless, that the operation of the valve stems in valve housing 12 are intended to effect the delivery to pump 21 of a fuel charge containing either normal engine fuel, or a mixture of normal fuel with an agent, and that the proportion of normal engine fuel in such mixture may be readily controlled by valves 17 and 18.

In Figs. 2 and 3 there is illustrated another valve or control assembly, consisting of a housing 27 provided with fuel inlet port 28 and an agent inlet port 29. These ports terminate in relatively narrow slots disposed at an angle to one another, so that liquids issuing under pressure through these ports will impinge upon each other and thereby mix with one another. The passage through these ports is controlled by rotary sleeve 30, provided with cylindrically shaped port control member 31. The latter has slanting edges 32 and 33, adapted to slide over ports 28 and 29, thereby controlling the amount of liquid passing through these ports. Obviously, port control member 31 may also completely close or open either of the two ports, as clearly shown in Figs. 2 and 3. The chamber in which sleeve 30 operates serves as a mixing compartment, and is provided with a single outlet 34 for the passage of a fuel charge into the pump. Sleeve 30 may be operated in any suitable manner, for instance by a gear 34'.

Another valve arrangement is illustrated in Fig. 4, consisting of a valve casing 35, in which operates a slide valve 36, provided with a body reduction 37. Slide valve 36 is intended to control elongated port openings 38 and 39, into which lead pipes 40 and 41, connected, respectively, with a fuel container, such as tank 10, and an agent container, such as tank 11, shown in Fig. 1. Below ports 38 and 39 is shown a mixing chamber 42 from which leads a conduit 43 to the injection pump.

Still another modified form of a valve structure is portrayed in Fig. 5, wherein is employed a casing 44 provided with inlet ports 45 and 46, controlled, respectively, by valve cones 47 and 48 of a valve member 49, the latter being operable by means of a gear 50, engaging teeth 51 provided in the valve member. Below the latter there is shown a mixing chamber 52, from which issues a supply pipe 53 leading to the pump. When gear 50 is rotated, valve member 49 may be moved to any desired degree in either direction, whereby ports 45 and 46 are controlled.

All of the aforescribed valve structures, designed for handling either undiluted normal engine fuel or mixtures of normal engine fuel with other liquids, do not provide means for mechanically mixing or emulsifying such fuel mixtures. In the embodiment illustrated in Fig. 6, mechanical mixing means are provided. In this device valve housings 54 and 55 are employed, in which operate, respectively, control valves 56 and 57, both connected by means of actuating lever 58, pivoted at 59. Leading into valve housing 54 is a conduit 60 for conveying a diluting agent to port 61. Into one side of valve housing 55 leads to control port 62 a conduit 63, which connects the port with a circulating pump 64. The latter receives through pipe 65 normal engine fuel from a fuel tank, such as container 10 of Fig. 1. From conduit 65 branches off through a T-fitting 66 another conduit 67 which is controlled by valve 68. From the other side of valve port 62 issues a connecting pipe 69, which leads to a chamber 70, wherein is mounted a turbine 71. Conduit 67 enters at 72 the bottom of chamber 70. Driven by turbine 71 is a shaft 73, provided with a plurality of paddles 74, and operating in a mixing chamber 75. Valve ports 61 and 62 are connected with chamber 75, so that when an agent and normal engine fuel enter the mixing chamber, they become thoroughly intermixed by paddles 74, before they can leave through passage

76, leading to pump cylinder 77, connected with the engine.

Inasmuch as normal engine fuel, supplied through pipe 65, is constantly circulated by rotary pump 64 in the system including pipe 63, valve housing 55, pipe 69 and pipe 67, turbine wheel 71 and paddle shaft 73 will always operate, as long as valve 68 is open. This valve serves for controlling the by-pass of the fuel entering 10 valve housing 55.

In connection with all of the devices illustrated, it is intended that only constant stroke compressors or injection pumps are used, so that fuel charges of uniform or constant volume will be 15 successively injected into the cylinder at all times. In consequence of maintaining a constant-volume fuel charge, the pressure at which such charge is injected will vary but little, even though the speed of the engine may change.

Aside from the employment of a constant-stroke pump system, delivering fuel charges of constant volume at a substantially constant pressure, it is essential, in order to have proper operation of the device, that the connection between 20 the fuel mixing instrumentality and the pump be as short as possible. This is necessary in order to preclude any segregation of the normal engine fuel from the diluting agent, while the mixture passes to the pump. Similarly it is also 25 essential that the connection between the injection pumps and the engine cylinders be made as short as practicable in order to eliminate as 30 much as possible any lag in engine response, due to changes in throttle settings.

It is to be noted, of course, that in the present invention the "throttle" is intended to control not the volume, but the effectiveness or power effects of full charges to be injected, and that these power effects vary in direct proportion to 40 the percentage of active or normal engine fuel contained in these charges. Thus when a fuel charge consists of 100% of normal or active engine fuel, its power effect will be at a maximum, while when the fuel charge is composed of say 45 50% of normal engine fuel and 50% of a diluting or diffusing agent, its power effect will be approximately one half of that maximum.

The term "approximately" is chosen with design, since in computing the power effect of a 50 mixed fuel charge, another important factor is to be taken into calculation, which factor may be considered a "by-product" of the present invention. It concerns what may be called "a fuel ionization effects," produced by injecting mixed 55 fuel charges containing water. The latter rapidly changes into vapor and promotes ignition and combustion of the injected fuel charge composition.

Referring again to the statement that the connections between the fuel mixing chamber and the injection pump, and between the latter and the engine cylinder are to be as short as possible, a proposed solution of this problem is illustrated in Figs. 7 and 8, wherein numeral 78 denotes the 60 engine cylinder, with which is closely connected a combination mixing valve and injection pump structure 79. The latter comprises a pump cylinder 80 in which reciprocates piston 81, driven by a grooved cam 82, shown diagrammatically. 65 The cam engages a roller 83, at the end of piston rod 83', which latter is conveniently guided, as 70 at

Pump cylinder 80 has a circumferential flange 84, made either integral with the cylinder body, or arranged separately, but conveniently joined

therewith. This flange supports a similarly flanged valve housing 85, which is bolted to the cylinder flange. The contacting surfaces joining the housing with the pump cylinder are sealed, as indicated at 86.

The outer surface of the pump cylinder, above flange 84, is machined, and a machined cylindrical recess 87 is provided in the valve housing adjacent to the outer machined portion of the pump cylinder. A cylindrical rotary sleeve valve 89, with an elevated extension 90 and a gear ring 91, is operatively mounted in recess 87, being actuated by gear 92. The latter is lodged in enlargement 93 of housing 85, and its drive shaft 94 extends from a bearing depending from cylinder flange 84.

Extension 90 of the rotary valve controls flat, horizontal inlet ports 95 and 96 issuing into the top of cylinder 80. These ports are aligned with corresponding passages 97 and 98 provided in housing 85. Extension 90 is equipped with recesses 99 and 100, adapted to either register with their respective ports and passages, or partly reduce their effective areas. The solid portions of extension 90 may close one or the other passage-way, such as shown in the figures at right.

Passages 97, 98 are connected by suitable fittings 101, 102 to tanks containing normal engine fuel and a diluting agent, such as shown at 10 and 11 in Fig. 1. Within each of the two fittings are preferably arranged check valves 103, see Fig. 7, opening towards the cylinder and closing during the compression stroke of piston 81. Inlet ports 95, 96 are disposed angularly, in the manner shown at 28 and 29 in Figs. 2 and 3, for the purpose of automatically intermingling the two components of the fuel charge, as they forcibly enter the pump cylinder. The latter serves in itself as a mixing chamber, whereby a connection between a separate mixing chamber and the injection pump, such as indicated at 20 in Fig. 1, is entirely eliminated.

In addition to this marked advantage, the proposed structure includes another improvement, in that the distance between the injection pump and the engine cylinder is shortened to a minimum. This is accomplished by providing a compact injection nozzle structure 104, see Fig. 7, which serves in the place of a close nipple, and which joins the pump and engine cylinders. The nozzle structure includes an exchangeable nozzle tip 105 and a spring-held check valve 106, the latter being adapted to open towards the engine cylinder at a predetermined injection pressure, for which the valve spring is adjusted.

The proposed combination mixing valve and injection pump structure of Figs. 7 and 8, while not intended to have any limiting effect upon my invention, not only clearly indicates the possibility of shortening or eliminating fuel charge transfer passages, but is also designed to facilitate the explanation of a new injection timing system, believed to have decided advantages over existing injection methods.

All the devices illustrated and described in the foregoing matter are primarily intended to deliver fuel charges at a constant volume and approximately at a constant pressure. Consequently, in order to change the speed or power of the engine, the only thing required is to change from normal engine fuel to a mixture containing the latter at a desired proportion. By altering such proportion, the power effect of the fuel charge is controlled. Thus when it is required to reduce the speed or power of an engine,

the normal engine fuel must be "diluted" by an agent having a lower combustion value than that of the normal fuel.

Inasmuch as the present invention contemplates the maintenance of injected fuel charges at a constant volume and under substantially a constant pressure, while only the combustibility of the fuel charge is altered for controlling the speed or power of an engine, accurate timing and control of the rate of fuel injection may be readily predetermined and kept constant, irrespective of throttle setting.

The action of a constant-strike injector pump, designed to inject fuel charges of a uniform volume, may be considered to consist of two major phases, i. e. suction and compression, and a minor phase, during the beginning of the compression stroke, which I shall term the starting phase. During this latter phase the piston is brought to a position at which a sharp "cut-off" of the fuel charge takes place, whereupon immediately follows the compression of the charge.

The aforesaid sharp fuel "cut-off" is facilitated by a bleeder or discharge passage 107 indicated in Fig. 7. This passage is governed by a spring-induced, outwardly opening check valve 108. Upon passing and closing bleeder passage 107, the piston locks the desired volume of the fuel charge in the cylinder, wherein it is now brought to the required injection pressure, at which nozzle valve 106 is opened to permit the injection of the compressed fuel charge into the engine cylinder.

When the full volume of a fuel charge is wholly injected, in one instance, into the engine cylinder, there occurs, instead of a relatively slow fuel combustion, a sudden, excessive detonation, followed by a sudden rise in pressure, which is highly undesirable, since when such pressure becomes excessive, it will cause "engine knocking."

In the lower part of Fig. 7 groove-cam 82 is designed to operate, in the direction of the arrow, about its axis 82'. The cam engages a follower or roller 83, mounted at the end of piston rod 83'. The cam design provides that when the cam is in its broken-line position I, piston 81 is at its inner dead center, practically contacting the cylinder head. As the cam turns through a 180° arc *a* towards its full-line position II, the piston moves to its outer dead center position and sucks in a fuel charge of the required volume. This outward piston movement is intended to be very rapid.

Now commences the inward or fuel charge compression and injection stroke of the piston. During the cam's rotation through the first half of arc *b*, towards the third indicated cam position III, the piston, starting from a point below bleeder passage 107, will, upon passing and closing the passage, immediately start compressing and injecting the fuel charge. The latter will be under practically the full required injection pressure. As the cam approaches the end of arc *b*, marked by radial line P, and continues in its movement through short arc *c*, to radial line P', an initial injection at a relatively slow rate takes place. As the cam rotation progresses from radial line P' through last arc *d*, the balance of the fuel charge is progressively injected at a relatively rapid rate. The initial fuel charge having been ignited, causes the ignition of the balance of the injected fuel charge.

While the foregoing explanation may leave with the reader a "slow-motion" impression, the actual time required for one complete working cycle of the device corresponds to only a very

small fraction of a second, and may be considered for all practical purposes an instantaneous action. The small difference between a full-volume, instantaneous fuel charge injection and the modified two-stage injection just described, is brought out clearly in Fig. 9.

In this diagram the volume or injection rate, and the time periods of two comparative types of fuel charge injections are indicated. Both are figured from the time the injector piston has passed bleeder passage 107 (Fig. 7), and has brought the fuel charge to the required injection pressure, at which complete atomization of the fuel charge is made possible. For simplicity's sake it is assumed that the injection pressure is the same for both injection types during their entire injection periods.

The full-line curve X represents a full-volume, instantaneous fuel charge injection, corresponding to the full and direct inward movement of the injection pump piston. The injection commences at 0, and ends at the top of the curve at X'. At that point the entire fuel charge has been transferred to the engine cylinder, and the pressure in the pump drops to zero, as indicated by the vertical downward portion of the curve, meeting the lower horizontal of the diagram near numeral 7.

The broken-line curve Y denotes a two-stage fuel charge injection, described in connection with Fig. 7. Between time divisions 2 and 3 curve Y progresses at a slant, indicating the initial injection and ignition period, the "cut-off" having taken place at time division 2. Curve Y further indicates that an initial fuel charge portion for the initial ignition period had taken place between divisions 2 and 3, and that, starting from division 3, the remainder of the fuel charge is injected into the engine cylinder.

The timing of fuel charge injections for the engine is best illustrated in Fig. 10. Assume that a full-volume fuel charge would normally be injected at a point advanced 10 degrees from the inner dead center of the engine piston. The initial injection and ignition of a portion of the fuel charge, indicated between points 2 and 3 of Figure 9, is preferably advanced in respect to the point of injection of the major fuel charge portion. An advanced point for an initial injection and ignition is indicated at a point marked "12 degrees." The light, initial fuel charge will ignite readily, and when the rest of the fuel charge is injected the heat within the cylinder will be sufficient to assure positive ignition of the whole charge.

Recapitulation

Comparing heretofore employed means for controlling the speed and power of engines with the present method and devices, the advantages of this disclosure become readily apparent, especially when considering the following important features:

1. The elimination of complicated and expensive fuel-metering devices and variable-stroke pumps and systems employing them, which latter are unreliable in operation because they are based upon the principle of reducing the volume of fuel charges for slowing down the speed or reducing the power of engines.

2. The maintenance of injected fuel charges at a constant volume.

3. The maintenance of the injected pressure at a substantially uniform value.

4. The resulting assurance of a uniform and

proper atomization of successive fuel charges at all speeds of the engine.

5. The possibility of providing for, and maintaining constant and accurate timing and the rate or manner of injection, which may be predetermined, as well as the effective power of the fuel charge.

6. The assurance of positive ignition of the injected fuel charge, whereby a high-speed engine may be safely idled down to a low speed without the danger of engine stoppage.

7. The maintenance of the engine at a safe working temperature, always.

8. The employment of devices, for accomplishing the desired results, which are simple in construction and, due to their simplicity, are reliable in their function and are inexpensive, being far less costly than similar unsatisfactory devices used heretofore.

Having thus described the present invention, and having pointed out the salient advantages thereof, it is to be borne in mind that the illustrations are not intended to disclose final structures, yet are indicative of the principles upon which the disclosed method, and the devices accomplishing it, are based, and that these illustrations are to serve purely for explanatory purposes, and that the method indicated, as well as the devices shown, may be altered and improved, and I therefore reserve for myself the right to effect such changes and improvements in both, within the broad scope of my invention, as expressed in the annexed claims.

I claim:

1. The method of controlling the operation of compression-ignition type internal combustion engines consisting of varying the combustibility, and therefore the effective power of solid fuel charges introduced into the engine without changing their volume, but by changing the potency of such solid fuel charges.

2. The method of controlling the speed and power of compression-ignition type internal combustion engines consisting of changing the effective heat value of introduced solid fuel charges without a change in their volume.

3. The method of regulating and varying the speed or power of Diesel engines consisting of introducing into an engine solid fuel charges at a constant volume and changing their combustibility by mixing the normal engine fuel with liquid agents having combustion characteristics different from that of the normal engine fuel.

4. The method of varying the speed or power of compression-ignition, injection-type internal combustion engines consisting of introducing into an engine fuel charges at constant volume and approximately at a constant pressure, and changing their effectiveness by changing their effective heat values immediately prior to their introduction into the engine.

5. The method of varying the speed or power of compression-ignition, fuel-injection type internal combustion engines by varying the combustion characteristics of fuel charges introduced into the engine at a constant volume, the method consisting of admixing with the normal engine fuel having certain combustion values an agent having different combustion values, prior to the introduction of the fuel charge into the engine.

6. The method of reducing the speed of high-speed Diesel type engines consisting of mixing the normal liquid engine fuel with a liquid agent having a lesser heat value than that of the normal fuel, prior to introducing the resorting solid fuel

charges into the engine, without either substantially altering the normal volume of, nor appreciably reducing the normal pressure at which such fuel charges are normally introduced into the engine.

7. The method of reducing the speed or power of compression-ignition, injection-type, high-speed internal combustion engines, which consists of mixing the normal liquid engine fuel with a liquid inert agent, and injecting the resulting mixture in the form of solid fuel charges at volumes and pressures substantially equalling normal fuel charges of normal engine fuel during normal engine operation.

8. The method of controlling the operation of high-speed compression-ignition engines, which consists of governing the combustion or power effectiveness of constant volume solid fuel charges, introduced at substantially uniform pressure, by changing the proportion of normal engine fuel in such fuel charges, and injecting and igniting first an initial solid fuel charge portion, followed immediately thereafter by the injection and ignition of the balance of the solid fuel charge.

9. The method of regulating the operation, as to speed or power, of compression-ignition, injection-type, high-speed internal combustion engines, which comprises changing at will from the normal engine fuel to a mixture containing a percentage of such normal engine fuel, and vice versa, and injection and igniting the resorting solid fuel charge in at least two stages.

10. The method, as stated in claim 9, effecting such mixture immediately prior to injecting it into the engine in the form of a solid fuel charge, introducing the latter at substantially the pressure and of a volume a fuel charge of normal engine fuel is being injected for operating the engine at its normal speed or power.

11. The method, as stated in claim 9, effecting such mixture immediately prior to injecting it into the engine in the form of a fuel charge, introducing the latter at substantially the pressure and of a volume a fuel charge of normal engine fuel is being injected for operating the engine at its normal speed or power, and changing the composition of the mixture, by altering the percentage of normal engine fuel in said mixture, while the engine operates, to effect changes in speed and power of the engine.

12. The method of regulating the speed or power of compression-ignition injection-type internal combustion engines, which comprises injecting into an engine cylinder and igniting there-in consecutive fuel charges of either normal engine fuel or of a liquid mixture containing such normal engine fuel, introducing and igniting such fuel charges in at least two continuous stages within one injection period, while maintaining the total volume and the injection pressure of such fuel charges substantially constant.

13. The method as stated in claim 12, said mixture constituting an emulsion of normal engine fuel with an inert agent, produced immediately prior to injecting it in the form of a fuel charge.

14. The method as stated in claim 12, said mixture constituting an emulsion of normal engine fuel with water, produced immediately prior to injecting it in the form of a fuel charge.

15. The combination with a Diesel type engine, of supply means containing normal engine fuel and other supply means containing a liquid

agent having combustion characteristics different from that of the normal engine fuel, and adjustable means for facilitating the mixing of normal fuel with the agent at any desired proportion to each other, prior to the introduction of a solid fuel charge into the engine.

16. The combination with an compression-ignition, injection-type internal combustion engine having constant volume fuel charge injection means, of supply means containing normal engine fuel and other supply means containing a liquid agent having combustion characteristics different from that of the normal engine fuel, means connected with said injection means for mixing, at any desired proportion to each other, said normal engine fuel with said agent, without affecting the operation of the constant volume injection means.

17. In a device for controlling the operation of high-speed Diesel engines by changing the combustion effects of a solid fuel charge while maintaining the latter at a substantially uniform volume, a mixing chamber having two controlled ports and a single outlet, regulable port control means in the mixing chamber for reducing or fully closing one of the ports, while simultaneously increasing or fully opening the other port, or vice versa, one of the ports being connected with a reservoir containing normal engine fuel, the other port being connected with a reservoir containing an agent having combustion characteristics different from that of the normal fuel.

18. In a device for controlling the operation of high-speed compression-ignition, injection-type engines by uniformly injecting solid fuel charges of constant volume and at a substantially constant injection pressure, but of different power effects, a valve structure having at least two controlled inlet ports, one for normal engine fuel and at least another for a different liquid, control means for said ports, operating means for said port control means adapted to reciprocally and simultaneously effect the closing and opening of the ports, a mixing chamber forming part of the valve structure, a constant-stroke injection pump closely connected and communicating with said chamber, and short connecting means provided with the pump for joining it with an engine cylinder.

19. In a device, as stated in claim 18, and means for agitating or mixing liquid in said mixing chamber.

20. In a device for changing the combustion or power effectiveness of fuel charges in compression-ignition fuel-injection-type engines, the combination with an engine cylinder of fuel charge injection means, adapted to deliver solid fuel charges of constant volume and at a substantially constant pressure, means for governing the combustion or power effectiveness of fuel charges, handled by said injection means, said governing means comprising a valve instrumentality controlling at least two inlet ports connected with normal engine fuel and a liquid agent mixible therewith, and means for operating said injection means and adapted to cause the latter to inject a solid fuel charge during one injection period in at least two immediately consecutive stages, the first stage being an initial injection and ignition stage.

HARLOW B. GROW.
